ABSTRACT

An orbiting-mass oscillator is coupled to a low-impedance elastomer in which a resonant standing-wave pattern can be established. The elastomer serves as a transmission and energy storage medium for the energy and is coupled to a free-standing heavy mass.

ELASTOMER RESONATOR FOR ORBITING-MASS OSCILLATOR

This application is a division of my application Ser. No. 666,398 filed Sept. 8, 1967, now U.S. Pat. No. 3,544,073.

In prior devices or systems utilizing sonic energy, elastomeric material such as rubber, for example, has been used as an isolator. As such, the elastomeric material prevented the dissipation of the sonic energy to areas not being worked upon. As is known, elastomers such as rubber can absorb vibratory energy such as is generated in acoustic resonators. In the prior art, an acoustic generator, such as for example an orbiting-mass oscillator, has been coupled to an elastic material such as steel, in which a standing-wave pattern could be generated. Such systems are taught in many of my issued patents wherein such combination of an orbiting-mass oscillator together with an elastic material such as steel have been utilized as an effective means for the transmission of resonant sonic energy. Never before have the unusual advantages to be attained by using an elastomeric material such as rubber for the resonator been appreciated.

The herein invention utilizes elastomeric material as a resonator element in a system utilizing acoustic energy. Preferably, the resonator element comprises a hollow thick-walled cylinder of an elastomeric material such as rubber or a rubberlike synthetic or natural material. Affixed to one end of the cylinder is an oscillator for generating acoustic waves in the resonator. Preferably, the oscillator is an orbiting-mass type such that a standing resonant wave is established and maintained in the resonator column. In one embodiment of the invention, the resonator can be coupled to a heavy mass, which in turn can drive an element such as a drill. The heavy mass between the elastomeric resonator and the drill tool acts, as will be explained, as a rectifier.

It has also been found that the elastomeric material interposed between the working tool and the support structure and housing therefor provides a compliant or low-impedance reactance which acts in the nature of a capacitive reflector to reflect the shock waves developed in the tool back to the tool so as to ameliorate their effects on the support structure and housing. It is to be noted that a similar shock wave amelioration is attained in the device shown in FIG. 3 of my U.S. Pat. No. 3,342,076 by virtue of the capacitive reactance of relatively low impedance fluid in chamber 44 and the high inductive reactance of body 55, and the device shown in FIG. 16 of my U.S. Pat. No. 3,352,369 by virtue of the capacitive reactance of air in chamber 88 and the high inductive reactance of housing 82.

It is also to be noted that all of the following of my applications disclose the above-indicated use of low-impedance material to provide a compliant reactance in combination with a massive housing: application Ser. No. 19,078, filed Mar. 31, 1960, for Oscillatory Fluid Stream Driven Sonic Generator with Elastic Autoresonator, now U.S. Pat. No. 3,111,931; application, Ser. No. 57,520, filed Sept. 21, 1960, for Sonic Earth Boring Drill with Elastic Fluid Resonator, now U.S. Pat. No. 3,163,240; application Ser. No. 443,997 for Sonic Driver with Pneumatic Capacitance, filed Mar. 30, 1965, now U.S. Pat. No. 3,277,970; application Ser. No. 459,754, filed May 28, 1956, for Low Impedance Isolator for Vibratory Pile Driver Machines, now U.S. Pat. No. 3,344,874; application Ser. No. 496,468, filed Oct. 15, 1965, for Sonic Resonator for Use with Sonically Driven Apparatus, now U.S. Pat. No. 3,342,076; my application Ser. No. 441,209, filed Mar. 19, 1965 for Sonic Method and Apparatus for Driving Anchors, Anchor Posts and the Like, now U.S. Pat. No. 3,352,369; my application Ser. No. 34,805 filed July 12, 1954, for Sonic Drilling by Rotating the Tool, now U.S. Pat. No. 3,211,243; my application Ser. No. 759,110, filed Sept. 11, 1968, for Method for Providing Efficient Sonic Coupling to the Earth in a Seismic Survey System, now U.S. Pat. No. 3,504,756; and my copending application Ser. No. 816,890, filed Apr. 17, 1969.

It is believed the invention will be better understood from the following detailed description and drawing of which:

The sole FIG. is a partially sectional view of an embodiment of this invention showing the elastomeric resonator utilized in combination with a drill.

It is helpful to the comprehension of this invention to make an analogy between a mechanical resonant circuit and an electrical resonant circuit. This type of analogy is well known to those skilled in the art and is described, for example, in Chapter 2 of "Sonics" by Hueter and Bolt, published in 1955 by John Wiley and Sons. In making such an analogy, force F is equated with electrical voltage E , velocity of vibration u is equated with electrical current i , mechanical compliance C_m is equated with electrical capacitance C_e , mass M is equated with electrical inductance L , mechanical resistance (friction) R_m is equated with electrical resistance R , and mechanical impedance Z_m is equated with electrical impedance Z_e . Thus, it can be shown that, if a member is elastically vibrated by a sinusoidal force, $F_0 \sin \omega t$, ω being equal to 2π times the frequency of vibration, then

$$Z_m = R_m + j(\omega M - 1/\omega C_m) = F_0 \sin \omega t / u \quad (1)$$

Where ωM is equal to $1/\omega C_m$, a resonant condition exists, and the effective mechanical impedance Z_m is equal to the mechanical resistance R_m , the reactive impedance components ωM and $1/\omega C_m$ cancelling each other out. Under such a resonant condition, velocity of vibration u is at a maximum, effective power factor is unity, and energy is most efficiently delivered to the object being vibrated. It is such a high-efficiency resonant condition in the elastic system being driven that is preferably utilized in the methods and devices of this invention to achieve the desired end results.

It is to be noted by reference to equation 1 that velocity of vibration u is highest where impedance Z_m is lowest, and vice versa. Therefore, a high-impedance load will tend to vibrate at relatively low velocity, and vice versa. Thus, at an interface between high- and low-impedance elements, a high relative movement results by virtue of such impedance mismatch which, as in the equivalent electrical circuit, results in a high reflected wave. This is accomplished in the embodiment of the invention where the elastomer resonator is coupled to a heavy mass which in turn is affixed to a chisel drill. High relative movement between the elastomer-coupled mass and drill results. Alternatively, where a low-impedance load, such as water, is present, the acoustic impedance of the elastomer so closely matches that maximum transfer of the vibratory energy is achieved. The mismatch of impedance arises at the interface of the water and parts submerged therein wherein the desired cleaning can occur.

Just as the sharpness of resonance of an electrical circuit is defined as the "Q" thereof, and is indicative of the ratio of energy stored to the energy used in each cycle, so also the "Q" of a mechanical resonant circuit has the same significance and is equal to the ratio between ωM and R_m . Thus, high efficiency and considerable cyclic motion can be achieved by designing the mechanical resonant circuit for high "Q."

Of particular significance in the implementation of the methods and devices of this invention is the high acceleration of the components of the elastic resonant system that can be achieved at sonic frequencies. It can be shown that the acceleration of a vibrating mass is a function of the square of the frequency of the drive signal times the amplitude of vibration. Under resonant conditions, the amplitude of vibration is at maximum and thus even at moderately high sonic frequencies very high accelerations are achieved.

In considering equation 1, several factors are to be noted. First, this equation represents the total effective resistance, mass and compliance in a vibrating circuit, and these parameters are generally distributed throughout the system rather than being lumped in any one component or portion thereof. Secondly, the vibrating system often includes surrounding components, a container holding the water and the water itself.

It is also to be noted that orbiting-mass oscillators are utilized in the devices of the invention that automatically adjust their output frequencies to maintain resonance with changes

in the characteristics of the load. Thus, in situations where we are dealing with parts which are placed in a bath during the operation of the device which will change that load, the system automatically is maintained in optimum resonant operation by virtue of the "lock in" characteristics of applicant's orbiting-mass oscillators. The vibrational outputs from such orbiting-mass oscillators are generated along a controlled predetermined coherent path to provide maximum output along a desired axis or axes. The orbiting-mass oscillator automatically changes not only its frequency but its phase angle and therefore its power factor with changes in the resistive impedance load to assure optimum efficiency of operation at all times. Such orbiting-mass oscillators are capable of efficiently generating high-level vibrational outputs.

By utilizing as a resonator element an elastomeric material such as rubber, a much greater feedback to the oscillator is accomplished than when the resonator is of a high-impedance material such as, for example, a steel column. This feedback results, since the elastomer, because of its inherently low impedance, provides a greater cyclic stroke for a given frequency at the point where the oscillator is connected. Previously, other low-impedance resonator elements such as air springs have been affixed to an oscillator. However, these elements have lumped constant impedance characteristics. On the other hand, the elastomeric material is a distributed constant system. A distributed constant system has the advantage of being able to accomplish an acoustic lever effect where, for example, a high velocity or amplitude vibration at the interface of the oscillator can be converted to a low velocity with a high force at the end of the resonator exposed to the load element.

Further, as indicated, one of the advantages of an orbiting-mass oscillator is its lock-in characteristics with the automatic adjustment of operating frequencies to accommodate for sudden changes in environmental reactive impedance. This feedback is best accomplished by a low-impedance resonator, such as the elastomeric element disclosed which has a large-amplitude vibration to better accomplish the feedback. Additionally, in this same vein, the automatic accommodation for changes in environmental resistive impedance caused by a work load is better fed back to the oscillator through a low-impedance resonator since there is greater activity where the resonator is coupled.

Turning now to the FIG., a C-shaped handle 91 is connected at a first end 93 to a plate 95 for supporting a motor 97. Extending downwardly from plate 95 and integrally formed therewith is an arm 99 connected at a pivot point 101 to a movable arm 103 which in turn is affixed to a drill chisel 105. Attached to a second end 107 of the handle 91 is a support arm 109 extending downwardly to an attachment ring 111 which may be of metal. The ring 111 surrounds and helps to support a tubular shaped elastomeric resonator 113. A portion of the ring 111 is additionally affixed to the arm 99 and connected therewith by means of bolts 114. Motor 97 drives oscillator 115 through a flexible shaft 117 connected therebetween. The output of oscillator 15 is coupled to a

platens 119 affixed to the top of the resonator element 13. The bottom of the resonator element is connected to a second platen 121 having a heavy mass 123 affixed thereto. Platens 119 and 121 are preferably vulcanized or glued with an epoxy resin to the elastomeric resonator 113 and thus integrally connected therewith. Heavy mass 123 is in contact with a raised portion 125 of the movable arm 103 directly in line with the chisel drill 105.

In the operation of the device, the motor which can be driven by means of electrical power provided through line 127 drives orbiting-mass oscillator 115, which may be of the type described in my U.S. Pat. No. 3,217,551, causing a standing wave 129 to be developed in the resonator element 113. The resonator element in turn drives heavy mass 123 against the raised portion 125 above the chisel drill. Since the mass is not attached to the portion 125 and the general movement of the resonator is in a vertical direction, the chisel drill will only move downwardly in response to the downward vibratory excursions of mass 123, causing a solely unidirectional action of the chisel drill. In this manner, effective rectification of the sonic energy is achieved. Pivot 101 permits the arm 103 to move the chisel drill downward into the ground as the heavy mass 123 strikes the portion 125 during the downward vibratory excursions of the resonator. Ring 111 surrounds the resonator element 113 at a nodal point so that a minimum or virtually no vibrational energy is dissipated into support arms 99 and 109 or carried back to parts such as handle 91.

It is to be noted that, while the device of the invention has been described as utilized in a chisel drill, the vibrational drive system disclosed can be utilized to equal advantage for driving other types of devices such as riveters, scrapers, woodworking tools, and the like.

I claim:

1. In combination, an orbiting-mass oscillator, an element to be energized, an elastomeric resonator element coupled in series between said element to be energized and said oscillator as a positive linkage therebetween, and means for driving said oscillator at a frequency such as to cause resonant elastic vibration of said resonator element, whereby substantially all of the vibratory energy generated by said oscillator is transmitted therefrom through said resonator element to said element to be energized.
2. The combination of claim 1 wherein said element is tubular.
3. The combination of claim 1 wherein said resonator element is coupled at one end to said oscillator, said element to be energized comprising a heavy mass coupled to the other end of said resonator element.
4. The combination of claim 3 and further comprising a tool disposed adjacent to said heavy mass, said tool contacting said mass whereby when said mass is caused to vibrate said tool will move in only one direction.
